UNITED STATES PATENT OFFICE.

HOWARD A. PEDRICK, OF BALA, PENNSYLVANIA, ASSIGNOR TO PEDRICK TOOL AND MACHINE COMPANY, OF PHILADELPHIA, PENNSYLVANIA, A FIRM CONSISTING OF ALBERT D. PEDRICK AND HOWARD A. PEDRICK.

RING-CUTTING MACHINE.

1,227,304.

Specification of Letters Patent. Patented May 22, 1917.

Application filed January 24, 1917. Serial No. 144,206.

To all whom it may concern:

Be it known that I, HOWARD A. PEDRICK, a citizen of the United States, and a resident of Bala, Montgomery county, Pennsylvania, have invented a Ring-Cutting Machine, of which the following is a specification.

One object of my invention is to provide a relatively simple, substantial and conveniently operated machine for simultaneously cutting a series of rings from a blank in the form of a tube;—the invention contemplating an arrangement of parts whereby it shall be possible to quickly and conveniently 10 adjust the machine to operate on tubes of different dimensions in order to adapt it to form rings of different diameters and widths.

A further object of the invention is to 20 provide a ring cutting machine with novel means for supporting the tube or blank from which rings are to be formed, which means shall not only be quickly adjustable to rigidly grip and hold said blank, but shall include a member adapted to removably 25 receive and grip any of a number of blank carrying elements of different external diameters.

Another object of the invention is to 30 provide a ring sawing machine with a novel construction and arrangement of blank holder and tool support, together with relatively simple and conveniently operated means whereby the distance between these 35 two elements may be quickly and easily adjusted.

These objects and other advantageous ends I secure as hereinafter set forth, reference being had to the accompanying drawings, in which,

Figure 1 is a side elevation of a ring cutting machine constructed according to my invention;

Fig. 2 is a vertical longitudinal section 45 taken through the tool- and blank-carrying shafts of my machine;

Fig. 3 is a vertical section on the line 3—3, Fig. 2; and

Fig. 4 is a transverse vertical section on 50 the line 4—4, Fig. 1.

In the above drawings, 1 and 2 represent two substantially similar castings held together by bolts 3 to form a hollow vertically elongated frame, open at the top and sub-

stantially rectangular in horizontal section; 55 the upper inside walls of said frame being suitably finished to serve as a guideway for a vertically movable carriage or cage 4.

Mounted within the upper part of the frame structure 1—2 is a bracket 5 having 60 a vertically threaded opening for the reception of a threaded spindle 6, fixed to but rotatable in the solid top portion of the carriage 4. Said spindle has fixed to its upper end a hand wheel 7, whereby it is possible 65 to raise or lower the carriage 4 in the frame.

The top part of said carriage has journaled in it a horizontally extending shaft 8, on one end of which is fixed a worm wheel 9 meshing with a worm 10 fixed to 70 or formed as part of a vertical shaft 11 carried in suitable bushings 12 and 13 projecting on one side of the frame member 1. The lower end of said shaft 11 has fixed to it a worm wheel 14 engaged by a worm 15 75 fixed to a short shaft 16 which likewise carries a pulley wheel 9a. The vertical side members of the carrier 4 are slotted to permit of the unobstructed inward projection of the bracket 5 in one case as well as of 80 bushings 17 carried by the frame members 1 and 2 respectively.

A hollow tool shaft 18 is mounted in these bearings and extends through the top of said frame on a line parallel with the shaft 85 8. Said tool shaft has fixed to it a pulley 19 connected by a belt 20 with the pulley 19a which in the present instance is formed integral with a spur gear 21 driven from a power shaft 22 through a pinion 23 fixed 90 to the latter in any desired manner.

That end of the tool shaft distant from the pulley 19 and gear 21, is formed with a tapering passage or recess to serve as a chuck for the reception of the correspondingly tapered end of a spindle 24, whose second end is journaled in a short standard 95 25 removably mounted on a projecting arm or table 26 bolted to the side of the frame member 2. This table is provided with a 100 horizontally extending slot for the reception of the head of a bolt 27 whereby while the standard 25 may be rigidly held in place, it may be removed at will by slackening off the nut on said bolt and sliding the 105 latter outwardly in said slot.

The tool spindle 24 has a fixed collar 28 between which and a nut 29 are clamped a

series of circular metal saws or milling tools 30 and these cutters or saws are spaced by circular washers 31 of definite thickness so that they are supported usually at definite distances apart. The blank carrying spindle 8 extends over the tool spindle 24 and its end is made tapering in form for the reception of a split sleeve 33 having an interior passage formed with the same taper as that of said end. Mounted on this sleeve 10 is a second split sleeve 34 designed to receive the blank α which is in the form of a hollow cylinder or tube. The extremity of the spindle 8 is threaded for the reception of a nut 35, between which and the end of the sleeve 33 is mounted a collar 36.

The above described machine is particularly designed to simultaneously form a number of similar rings for use in the manufacture of piston rings for internal combustion engines and similar machines, and in preparing my machine for use for this purpose, I place on the tool spindle 24 a series of circular saws or cutters, alternating 25 with them washers 31 whose thickness is substantially equal to the width of the rings which it is desired to form. These saws and washers are then held rigidly clamped on the spindle by the nut 29, and 30 after the tapering end of said spindle has been inserted in the correspondingly formed recess of the tool shaft 18, the standard 25 is engaged with the end of said spindle. The nut on the bolt 27 is then set up, so that 35 the tool provided by the assembled saws is ready for use.

The tube or blank from which the rings are to be cut is then placed on the sleeve 34, whose external diameter is normally such 40 as to permit its easily entering said blank, and it likewise is bored to easily fit on the external surface of the second split sleeve 33. These two concentric split sleeves 33 and 34 with the blank are then mounted on 45 the tapering end 32 of the shaft 8 and after the collar 36 is placed over the threaded end of said shaft, the nut 35 is set up against the end of the sleeve 33. The latter is thus forced onto the tapering end 32 so as to 50 expand it and cause it in turn to expand the sleeve 34 which thus rigidly grips and holds the blank α from movement.

Power is then applied to turn the driving shaft 22, which through the pinion 23 and 55 gear 21 turns the tool shaft 18 and the tool comprised by the saws carried by the spindle 24. At the same time power is transmitted from the pulley 19 through the belt 20, pulley 19^a, shaft 16, worm 15, worm 60 wheel 14, shaft 11, worm 10 and worm wheel 9 to the shaft 8 carried by the carriage 4, which thus turns with the blank α . By suitable rotation of the hand wheel 7, the carriage 4 is then lowered to bring the 65 rotating blank into engagement with the

rotating saws and this adjustment is made possible by reason of the peculiar mounting of the worm wheel 9 and worm 10.

The driving mechanism and gearing above described is so designed that the saws 70 are turned at a more rapid rate than is the blank α and that in an opposite direction to said blank, the adjustment of the carriage being such that the saws cut to a depth equal to the thickness of the blank. 75 With this arrangement of parts it is merely necessary for the machine to continue operation for a time sufficient to permit the blank-carrying shaft 8 to make one complete revolution, since by such an operation 80 the blank is cut into a number of rings which may thereafter be subsequently operated on to give them the finish and other characteristics required of piston rings.

By the above means, it is not only possible 85 to rapidly make a number of similar rings but after the completion of the operation, they may be quickly removed from the machine by slackening off the nut 35 and another blank put in position to be cut. 90 Moreover by the use of the two concentric sleeves 33 and 34, I am enabled to reduce the cost of manufacture of the rings as well as the maintenance charges of the machine, since even though the saws should cut into 95 and ultimately require the replacement of the sleeve 34, (which is merely an inexpensive cylindrical shell) the more costly inner sleeve with its tapering bore would never be injured nor require replacement. 100

Obviously, if it be desired to manufacture rings of different sizes from those shown in the drawings, the outer sleeve 34 may be replaced by another sleeve of the required external diameter but having an internal diameter such as to permit it to be easily fitted onto the inner sleeve 33. 105

The carriage 4 may be conveniently adjusted on the frame not only to permit of the proper engagement of the blank by the 110 saws but also to suit the machine for operation on blanks of different diameters.

I claim;—

1. The combination of a hollow frame having an internal guideway; a carriage 115 projecting into said frame and slidably on the guideway; two substantially parallel shafts respectively supported by the carriage and the frame; means for rotating said shafts; a plurality of substantially parallel cutters on one of the shafts; and means on the other shaft for supporting a tubular blank in position to be engaged by said cutters simultaneously.

2. The combination of a hollow frame 125 having an internal guideway; a carriage projecting into said frame and slidably on the guideway; two substantially parallel shafts respectively supported by the carriage and the frame; means for rotating 130

5 said shafts; a plurality of substantially parallel cutters on one of the shafts; means on the other shaft for supporting a tubular blank in position to be engaged by said cutters simultaneously; with a screw for adjusting the carriage on the frame to vary the distance between the shafts.

10 3. The combination of a hollow frame having an internal guideway; a carriage projecting into the frame and slideable on the guideway; a bracket having a threaded opening and mounted within the hollow of the frame in position to project adjacent the carriage; a manually adjustable threaded spindle 15 on the carriage extended within the threaded opening of said bracket; two substantially parallel shafts respectively supported by the carriage and the frame; means for rotating said shafts; a plurality of substantially parallel cutters on one of the shafts; and means on the other shaft for supporting a tubular blank in position to be engaged by said cutters simultaneously.

20 4. The combination of a frame; a carriage 25 movably guided thereon; two parallel shafts supported respectively on the carriage and on the frame; a plurality of parallel cutters on one of the shafts; means for holding a tubular blank on the other shaft; means for 30 adjusting the carriage on the frame to vary the distance between said shafts; and driving means for the shafts including a worm wheel on the carriage-supported shaft and a driven worm extending in a line parallel 35 to the line of movement of the carriage in engagement with said worm wheel.

5. The combination of a frame; a carriage 40 slidably guided thereon; two parallel shafts respectively carried by the frame and said carriage, one of the shafts including a chuck portion; a spindle having one of its ends removably fitting said chuck portion; means for supporting the other end of said spindle; a series of parallel cutters fixed to the spindle so as to turn therewith; means for 45 non-rotatably holding a tubular blank on the second shaft; and means for driving said shafts.

6. The combination of a frame; a carriage 50 movably guided thereon; two parallel shafts respectively carried by the frame and by said carriage; means for driving said shafts; a series of parallel spaced cutters fixed to one of the shafts; a split internally tapered sleeve fitted to a tapered portion of 55 the second shaft; a cylindrical split sleeve mounted on said first sleeve for the reception of a tubular blank; with means for moving the first sleeve on the shaft to expand it and thereby expand the second 60 sleeve.

7. The combination of a frame; a carriage 65 slidably guided thereon; two parallel shafts respectively carried by the frame and said carriage; a series of parallel cutters fixed to one of the shafts so as to turn therewith; means for non-rotatably holding a tubular blank on the second shaft; and means for driving said shafts.

In witness whereof I affix my signature. 70

HOWARD A. PEDRICK.
